UNITED STATES PATENT OFFICE.

CLARE H. DRAPER, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

SHUTTLE-BOX TENSION-CONTROLLING MECHANISM FOR LOOMS.

Application filed November 7, 1924. Serial No. 748,339.

The present invention relates to shuttle box tension controlling mechanism for weft replenishing looms of the bobbin changing type.

In looms of this type the positioning of the shuttle in the shuttle box under the weft replenishing mechanism is of importance in order to secure the efficient and certain operation of the weft replenishing mechanism. The shuttle is not required to have a precise position in register with the weft replenishing mechanism as the inclined guide of the shuttle permits its being moved by the bobbin or the movement of the bobbin by it within the limits of the length of the guide. In order to facilitate such movements of the shuttle in order to cause it to adjust its position to the position of the bobbin presented to it by the transerrer, it is proposed according to the present invention to relieve the pressure on the binders on the shuttle so as thereby to facilitate its movement under the influence of the pressure of the bobbin butt either lengthwise of the lay or transversely thereto.

The object of the invention, therefore, is to produce a shuttle box tension controlling mechanism for looms of the bobbin changing type having provision for relieving the shuttle tension during replenishment. To this end the invention consists in the construction hereinafter described and particularly defined in the claim.

In the accompanying drawings illustrating the preferred form of the invention, Figure 1 is an elevation partly in section of a portion of a loom embodying the features of the present invention, the lay being shown in approximately front center position; Figure 2 is a detail of the binder releasing device; Figure 3 is a plan view of the parts in front center position; and Figure 4 is a front elevation of some of the parts shown in Figure 3.

The illustrated embodiment of the invention is described in connection with the shuttle box tension controlling mechanism illustrated and described in the application of Jonas Northrop filed August 12, 1924, Serial No. 731,548.

The illustrated embodiment of the invention is described as follows: The lay 5 is supported on the sword 6 provided with the usual shuttle box 7. The dagger shaft 8 is

supported on the lay in the usual manner, and carries binder fingers 9 and the dagger 10. Attached to the dagger shaft is the fork 11, one arm 12 of which has a hole in its end which receives the lateral pin 13 of the tension rod 14. The lower end of the tension rod passes through a hole in the collar 15 pivotally mounted at 16 in a bracket 17 bolted to the frame 18 of the loom. A spring 19 on the lower end of the rod below the collar takes against such collar at its upper end and against the adjusting nut 20 at its lower end, being secured in adjusted position by the lock nut 21. The spring 19 normally tends to pull upon the arm 12 and to turn the dagger shaft 8 in a direction to cause the dagger to strike the steel 22 of the frog 23. This pull upon the tension rod 14 causes pressure to be exerted upon the shuttle binders 24 to cause proper tension to be exerted on the shuttle as it enters the shuttle box.

The arm 12 also carries a spring stop 25 which is supported in an ear 26 projected laterally from the arm 12. A spring 27 embraces the shank of the stop 25, taking against the upper surface of the ear at its lower end and against the head of the stop 25 at its upper end. The stop 25 is provided on the under side of the ear 26 with an adjusting nut 28, which is secured in adjusted position by the locking nut 29. This stop 25 is a dagger stop and serves to prevent overthrow of the binders by the entering shuttle.

The fork 11 also bears a second arm 30, on the forked end of which is pivoted at 31 a by-pass pawl 32. The by-pass pawl is normally held in the position shown in Fig. 1 by the spring 33 attached to the laterally extended lug 34 on the upper end of the by-pass pawl 32 at the forward end of the spring, and by means of the strap 35 attached at its rear end to the sword 6 of the lay. The by-pass pawl carries a roller 36 which is adapted to engage a cam 37 adjustably secured by the bolt 38 to the bracket 39 secured to a rearward projection 40 from a portion of the frame of the loom.

The operation of the mechanism as thus far described, which is the construction illustrated and described in said application, is as follows: Starting with the lay on the back center, assuming the shuttle box to

contain a shuttle which presses upon the binder 24 and thereby holds the binder finger 9 in rearward position, the dagger 10 will be held in raised position thereby during the forward movement of the lay. During such movement the by-pass pawl 32, as it advances, comes into engagement with the surface of the cam 37. The pawl is turned to the right, as viewed in Fig. 1, stretching the spring 33, and the roll 36 rides up over the cam without any effect upon the position of the dagger, the by-pass pawl yielding as it passes over the cam. After the by-pass pawl passes beyond the cam, it snaps back to normal position under the influence of its spring, so that at the end of the forward movement of the lay the by-pass pawl occupies its normal position with respect to the fork upon which it is carried, as shown in full lines in Fig. 1. During this forward movement of the lay, the tension rod 14 pulls downwardly upon the fork 12 and thereby tends to turn the dagger down into position to engage the frog. But inasmuch as the assumption is that a shuttle occupies the box at this time, no turning movement is imparted to the dagger. During the backward movement of the lay the by-pass pawl 32 rides up over the cam 37 and by reason of the engagement of the projection 34 therefrom, which rests upon the upper surface of the arm 30 of the fork 11, it lifts the fork 11 and thereby turns the dagger shaft and relieves the binder of the pressure of the dagger fingers during the time the roll on the by-pass pawl is in engagement with the cam. This release of the pressure on the binders due to the dagger fingers occurs at a time when the shuttle is being picked. The relief of the binders from this pressure due to the tension rod 14 is momentary and for the purpose of facilitating picking of the shuttle and reducing the power required for that purpose and rendering more certain and uniform the force imparted to the shuttle, as well as to diminish the force required in picking. As soon as the roll of the by-pass pawl passes off of the tension controlling cam 37, the pressure of the fingers upon the binders is restored by the pull of the tension rod 14 on the dagger rod fork 11. As the lay retreats, the pres-

sure exerted by the tension rod 14 on the dagger fingers increases, so that the shuttle tension, that is to say, the pressure exerted by the binders on the shuttle as it enters the box, increases from the time the tension is first applied all of the way back to back center.

The arm 30 is also provided with a cam roll 41 mounted on the stud 31, which is adapted to engage a holder finger 42 which is secured to the change shaft 43. This holder finger is shown in Fig. 1 as occupying its lower position, and while in this position it does not engage the roller 41 of the fork 11. But when the change shaft is turned to lift the transfer latch so as to cause replenishment, the holder finger is raised and upon the next forward beat of the lay the cam roll 41 engages the surface of the holder finger 42 and is thereby lifted so as to turn the dagger shaft 8 and withdraw the fingers 9 from contact with the binder 24. The binders preferably have a light spring for holding them with a small pressure against the shuttle so as to prevent accidental movement thereof, and when transfer is called for, therefore, the binders are released from the heavy pressure applied through the dagger shaft so that the shuttle is free to be moved by the entering bobbin.

The present invention has been shown in connection with the construction illustrated in the said application, but it is to be understood that it may be embodied in other forms within the scope of the claim.

Having thus described the invention, what is claimed is:

A weft replenishing loom of the bobbin changing type having, in combination, weft replenishing mechanism including a change shaft, a lay having shuttle boxes provided with binders, a dagger rod on the lay, binder fingers on the dagger rod, a forwardly extended lever on the dagger rod, a rearwardly extended lever on the change shaft cooperating with the lever on the dagger shaft to turn the dagger shaft to relieve the pressure on the binders when the change shaft is operated to cause weft replenishment.

In testimony whereof I have signed my name to this specification.

CLARE H. DRAPER.
